CONTAINER FOR INSTANT OR PRECOOKED RICE AND THE LIKE

Lawrence Lynn and Roy M. Anderson, both of Houston, Tex., assignors to Riviana Foods Inc., a corporation of Delaware

Filed May 24, 1965, Ser. No. 458,021
8 Claims. (Cl. 215—56)

This invention relates to a container. More particularly, this invention relates to a container made of impervious material and including a means to allow the free circulation of air into and out of the interior of the container.

In the packaging of certain products, particularly instant or precooked rice and other cereal grains, a problem arises in that such products, after they are packaged, tend to develop oxidative rancidity and the protein in the products undergoes a hydrolytic breakdown. The resulting rancid and haylike odors and flavors in the product and headspace of the product container are objectionable to the consumer, and adversely affect the saleability of the product.

A number of solutions for the above-mentioned problem have been proposed by the prior art. One solution is to package the product in an air-tight container, and to fill the container with an inert gas, or to evacuate it. Another solution consists of using an antioxidant in the product to be packaged in the air-tight container. However, all of these proposed solutions or remedies are generally undesirable, either because they provide inadequate protection for extended periods of time, are aesthetically displeasing, or are not in keeping with the best or allowable practices of the Food and Drug Administration.

It has been found that when instant or precooked rice is packaged in a pervious container, its tendency to become rancid and develop odors is greatly reduced. However, the pervious or breatheable containers used in the art are generally made of a permeable film or paper board, which, while they allow air to circulate to and from the container's interior, to suffer from certain disadvantages. Since these materials are permeable and, to some extent, not rigid, they do not provide such protection for the product as would be afforded by an impervious container. Furthermore, these materials do not, generally speaking, readily lend themselves to the manufacture of containers which are highly attractive to the consumer, and, particularly, to the manufacture of containers which may be considered "premium" or "specialty" items of value to the consumer after the product contained therein has been removed.

It is therefore an object of our invention to provide a container which is made of an impervious material, together with means to allow the free circulation of air between the interior of the container and its exterior.

It is a further object of our invention to provide a container made of an impervious material, together with means allowing the free circulation of air between the interior of the container and its exterior while the lid of the container is secured to the lower portion of the

It is a discovery of our invention that a container may be provided, particularly for instant or precooked rice and other cereal grains, whose lid and lower members are made of an impervious material, and which includes means spacing the lid and lower members and a tape securing the lid to the lower member while allowing air to pass said tape to the interior of the container, thus permitting precooked, dehydrated rice and other cereal grains to be packaged in such container for extended periods of time without developing rancidity or off flavors.

2

These and other objects and advantages of our invention will become apparent upon consideration of the following description taken in conjunction with the accompanying drawings, in which:

5 FIGURE 1 is side elevational view, partially in section, of one embodiment of the container of our invention;

FIGURE 2 is a transverse sectional view taken on line 2—2 of FIGURE 1, the left-hand half thereof being a view taken in an upward direction, and the right-hand half being a view taken in a downward direction;

10 FIGURE 3 is a sectional view taken on line 3—3 of FIGURE 2;

FIGURE 4 is a side elevational view, partially in section, of the upper portion of a second embodiment of 15 the container of our invention;

FIGURE 5 is a sectional view taken on line 5—5 of FIGURE 4; and

20 FIGURE 6 is a perspective view of a pair of spacers and portions of the tape and upper and lower members of the embodiment of FIGURE 4.

Referring now to FIGURE 1, one embodiment of the container of our invention is shown in its assembled condition. The container consists of an upwardly extending hollow lower member 1, having a closed lower end 2 and an open upper end, and a lid or upper member 3. The lower and lid members are typically of circular cross section, and each is made of an impervious material, such as glass.

25 At the upper end of lower member 1 there is a circumferentially extending rim 4, and near the lower end of upper member 3, but spaced above the lower end thereof, there is a circumferentially extending downwardly facing ridge or shoulder 5, which is adapted to rest upon rim 4 of lower member 1. When the lower and upper members 1 and 3 are made of glass, and particularly when it is desired that the container have an attractive appearance, we prefer to utilize therefor the jar and lid components of a conventional apothecary jar, as shown in the drawings.

30 In order to allow the free circulation of air between the interior and exterior of the container, it is necessary to provide suitable means for holding the upper member 3 in spaced relationship away from the upper end of lower member 1. In the embodiment of our invention illustrated

35 in FIGURE 1, such means is provided by one or more imperforate spacers 6, typically three in number, which are positioned on the upper rim 4 of lower member 1 and circumferentially spaced from each other on the rim, as shown in FIGURE 2. The illustrated spacers are formed

40 by longitudinally slitting a number of short lengths of resilient tubing, such as plastic tubing, and then snapping the lengths of tubing over rim 4 so that the longitudinal edges formed by the slit are respectively positioned abutting the interior and exterior surfaces of the lower member 1, as shown in FIGURE 1. With spacers 6 in position,

45 they project above rim 4 so that shoulder 5 of upper member 3 will rest thereon, and air may pass between the interior and exterior of the container through the resulting spaces 8 defined by the spacers, shoulder 5, and the upper edge of lower member 1.

50 In order to secure upper member 3 to lower member 1, a length of tape 9 is wrapped around these members so as to cover the spaces 8 and spacers 6. To allow air to pass through the tape and to circulate between the

55 interior and exterior of the container, tape 9 has provided therethrough a number of perforations 10, and is wrapped around the container in such a position that at least a portion of the perforations 10 overlie and communicate with spaces 8. The upper and lower edges of the tape re-

60 spectively overlap the lower edge of upper member 3 and the upper edge of lower member 1, securing these

65

70

75

two members together. The tape 9 may be an adhesive tape, however we prefer to employ a commercially well known shrinkable polyethylene tape. The polyethylene tape should be of such width that the upper edge thereof overlaps the upper edge of ridge or shoulder 5 on upper member 3. Before applying, the polyethylene tape is dipped in a solution of glycerine and water, and applied when wet. As the tape dries, it shrinks and tightens about lower and upper members 1 and 3, holding them together.

As shown in the drawings, upper member 3 may be bell-shaped, with an upwardly extending hollow portion 11 therein. A circumferentially extending upwardly facing shoulder 12 extends into hollow portion 11, corresponding to the lower edge of ridge or shoulder 5. For display purposes, an ornament, such as artificial flower 13, may be placed within hollow portion 11. To support the ornament, we provide a disc 14 of cardboard or plastic, which has radial, circumferentially spaced slits cut in its outer periphery (as shown in FIGURE 2), and which rests upon shoulder 12. The slits allow additional air circulation between the upper hollow portion 11 and lower member 1, while preventing the instant rice or other product 16 in the lower member from entering the portion above the disc 14.

In one use of the container of FIGURE 1, instant or precooked rice or other cereal grain 16 is placed within lower member 1, and upper lid member 3, containing ornament 13 and disc 14, is placed with its shoulder 5 resting on the spacers 6 located on rim 4 of lower member 1. A strip of perforated tape 9 is then wrapped around upper and lower members 1 and 3 at the juncture thereof to secure the members together. If the tape is of the adhesive variety, it is merely stuck to each of the members; if it is a shrinkable polyethylene tape, it is applied in the manner described above.

With the container in its assembled condition, air may circulate through perforations 10 in tape 9 and the spaces 8 between lower and upper members 1 and 3 to the interior of the container, and vice versa. As described heretofore, this air circulation is important in that it prevents the development of rancidity and rancid odors in the packaged product. We have found that when instant rice is packaged in the container of our invention it will retain its freshness and flavor and not become rancid for an extended period of time, substantially in excess of the time the packaged precooked rice or other cereal grain would normally be retained in the container before use. At the same time, the imperviousness of the material from which the upper and lower members of our container is made provides protection of the packaged product superior to that afforded by packages made of "breatheable" film or paper board.

In FIGURE 4 of the drawings we have illustrated a second embodiment of our invention, in which it is unnecessary that the adhesive or shrinkable polyethylene tape 9' be provided with perforations. In this embodiment, each imperforate spacer 6' consists of a length of cardboard or plastic bent in half and placed on rim 4 of lower member 1, with the bend uppermost and the two ends of the spacer respectively positioned adjacent the interior and exterior surfaces of lower member 1.

Only one spacer 6' need be used, however we prefer, for reasons which will become apparent, to employ three pairs of spacers on rim 4, as shown in FIGURE 5. The three pairs of spacers are placed on rim 4 in equally spaced circumferential positions, with a gap between the two spacers of each pair.

As mentioned above the tape 9' used in this embodiment of our invention need not be perforated, and we prefer to employ an unperforated tape, as shown, which may be an adhesive or shrinkable polyethylene tape as described above with respect to the embodiment shown in FIGURE 1. With the shoulder 5 of upper member 3 resting on spacers 6', spaces 8' will be defined by shoulder 5, spacers 6', and the upper edge 4 of lower member

5 members 1 and 3. The tape 9' is then wrapped around the circumference of the container in such a position that its upper edge overlaps the upper edge of ridge or shoulder 5, and its lower edge overlaps the upper end of lower member 1 and the ends of the spacers 6' which are adjacent the lower member's outer surface, in the manner shown.

With tape 9' wrapped around the container in this fashion, it is apparent that it will not contact the outer surface of lower member 1 immediately adjacent the edges of spacers 6', because of the thickness of the spacers. As is more perspicuously illustrated in FIGURE 5, there will therefore be a space 17 between the edge of each spacer 6' and the point at which tape 9' first contacts the outer surface of lower member 1, which spaces 17 are in communication with spaces 8', and thus with the interior of the container.

When three equally spaced pairs of spacers are used, as described above, each pair of spacers is so positioned that the gap between the two spacers of each pair is such that tape 9' will not contact the outer surface of lower member 1 within the gap. Thus, besides spaces 17, a relatively large space 18 is left between each pair of spacers, tape and lower member, allowing air to circulate more freely between the interior of the container and its exterior.

In one use of the container of FIGURE 4, instant or precooked rice or other cereal grain 16 is placed within lower member 1 and spacers 6' are positioned on the rim 4. Upper member 3, containing ornament 13 and disc 14, is placed on the spacers and tape 9' wrapped around the two members to secure them together, with the lower edge of the tape overlying the ends of the spacers. Air may then circulate between the interior and exterior of the container through spaces 17, 18 and 8', as described above.

When the product packaged within either embodiment of the container through spaces 17, 18 and 8', as described otherwise removed therefrom, the container may then be utilized in a conventional manner. This is accomplished simply by removing spacers 6 or 6' from upper rim 4 of the lower member 1, whereupon the shoulder 5 of upper or lid member 3 may rest directly on rim 4, affording a container which is substantially air tight and may be put to a variety of uses.

While our invention has been described with respect to a glass container, it is also applicable to containers made of other impervious materials, such as metals or impervious plastics. Generally, the choice of material will depend upon the particular use to which the container is to be put; usually, glass is desirable where the container is to be displayed for sale to the consumer.

Having described our invention with reference to certain particular embodiments and examples, it is understood that it is not intended to be limited thereto, but includes such modifications as may occur to those skilled in the art within the spirit of the invention as defined by the appended claims.

We claim as our invention:

1. A container for instant rice and the like comprising, a hollow upwardly extending lower member closed at its lower end, an upper lid member having a downwardly-facing shoulder adapted to engage the upper end of said lower member, each of said members being made of an impervious material, a plurality of spacers carried by said upper end of said lower member and circumferentially spaced from each other thereon, each of said spacers including a downwardly-extending portion adjacent the exterior surface of said lower hollow member, said shoulder of said upper member resting on said spacers,

whereby a plurality of spaces are defined by said shoulder, upper end and spacers, and a length of tape wrapped around said upper and lower members, with the upper edge of said tape overlying and secured to a portion of said upper member and the lower edge of said tape overlying said portions of said spacers and secured to said lower member for a portion of the distance between at least two of said spacers,

whereby a plurality of spacers are defined by said spacer portions, tape and lower member, and air may pass between the interior and exterior of said container through said pluralities of spaces.

2. The container of claim 1, wherein said impervious material comprises glass.

3. A container comprising, a hollow upwardly extending lower member closed at its lower end,

an upper lid member having a downwardly-facing shoulder adapted to engage the upper end of said lower member,

each of said members being made of an impervious material,

a plurality of spacers carried by said upper end of said lower member and circumferentially spaced from each other thereon,

said shoulder of said upper member resting on said spacers,

whereby a plurality of spaces are defined by said shoulders, upper end, and spacers,

a length of tape wrapped around said upper and lower members, with the upper edge of said tape overlying and secured to a portion of said upper member and the lower edge of said tape overlying and secured to a portion of said lower member,

said tape having a plurality of perforations therethrough, and

said tape being so positioned with respect to said upper and lower members that at least a portion of said perforations overlie said spaces,

whereby air may pass between the interior and exterior of said container through said perforations and spaces.

4. The container of claim 3 wherein said upper and lower members are made of glass, and 45 said upper member has an upwardly extending hollow portion therein, an ornament, and means supporting said ornament within said hollow portion.

5. A container for instant rice and the like, comprising, a lower hollow member closed at its lower end, an upper lid member for said lower member, both of said members being made of an impervious material, engaging means on one of said members adapted to engage the other of said members,

at least one imperforate spacer means supported by said other of said members and in engagement with said engaging means on said one of said members, securing means securing said upper lid member to said lower member while allowing air to circulate thereto past the space provided between said upper and lower members by said spacer means, and

said securing means comprising a length of tape having perforations therethrough, said tape being so positioned that at least a portion of said perforations are in communication with said space.

6. The container of claim 5 wherein said spacer means is supported on the upper end of said lower member and comprises a length of resilient tubing longitudinally slit down one side thereof, with the edges of the slit respectively abutting the interior and exterior surfaces of said lower hollow members.

7. The container of claim 5, wherein said spacer means includes a portion thereof adjacent the exterior surface of one of said upper and lower members, and said securing means comprises a length of tape partially overlying said portion of said spacer means whereby a space is defined by said tape, exterior surface and portion of said spacer means, said last-mentioned space being in communication with said space provided by said spacer means between said upper and lower members.

8. The container of claim 7, including at least a pair 35 of said spacer means, said portions of said spacer means being sufficiently close to each other that the portion of said tape extending between said spacer means is maintained out of contact with said exterior surface of said lower member.
